[57] CLAIM

The ornamental design for a writing instrument having light reflective surfaces, as shown and described.

DESCRIPTION

FIG. 1 is a side elevational view of a writing instrument having light reflective surfaces showing our new design, all other sides being identical thereto;

FIG. 2 is a top plan view thereof;

FIG. 3 is a bottom plan view thereof; and,

FIG. 4 is a cross-sectional view taken along lines 4—4 of FIG. 1 illustrating in cross-section, the inner and outer surfaces and spiral shaped surface discontinuities thereon.
